(57) **CLAIM**

I claim the ornamental design for a bottle with cap, as shown and described.

DESCRIPTION

FIG. 1 is a perspective view showing my new design for a bottle with cap;

FIG. 2 is a rear elevation view thereof;

FIG. 3 is a front elevation view thereof;

FIG. 4 is a left side elevation view thereof;

FIG. 5 is a right side elevation view; and,

FIG. 6 is a top plan view thereof.
